Patented Aug. 22, 1922.

UNITED STATES PATENT OFFICE.

HOWARD PARKER, OF BERLIN, NEW HAMPSHIRE, ASSIGNOR TO BROWN COMPANY,
OF BERLIN, NEW HAMPSHIRE, A CORPORATION OF NEW HAMPSHIRE.

CRANE.

1,426,764.

Specification of Letters Patent. Patented Aug. 22, 1922.

Application filed August 2, 1920. Serial No. 400,601.

To all whom it may concern:

Be it known that I, HOWARD PARKER, a citizen of the United States, and a resident of Berlin, county of Coos, State of New Hampshire, have invented certain new and useful Improvements in a Crane, of which the following is a specification.

This invention relates to a crane peculiarly adapted for use in conveying rolls of paper or the like and the invention has as its object to provide a simple apparatus of this sort with which articles may be quickly transported without injury.

In the accompanying drawing, wherein the preferred embodiment of the invention is illustrated,

Fig. 1 is an elevational view of the apparatus, parts being broken away and a roll of paper being shown in dotted lines carried thereby.

Fig. 2 is a sectional view taken on line 2-2 of Fig. 1 and looking in the direction of the arrow.

Fig. 3 is a sectional view taken on line 25 3-3 of Fig. 1.

Fig. 4 is an enlarged view of the bar by means of which the article transported may be attached to the chains of the crane, the bar being illustrated as positioned with- 30 in the core on which a roll of paper or the like is wound.

Referring to the drawing in detail, the device of the present invention comprises generally a boom *a* adapted to be suspended from a travelling crane or derrick (not shown); a pair of carriages *b* adjustable longitudinally of the boom and carrying chain *c*; and means operated by the hand wheel *d* for simultaneously moving the carriages *b* in opposite directions on the boom *a*.

The boom *a* is formed of two angle iron beams 10 positioned with their horizontal webs extending in opposite directions. The vertical webs of the beams 10 are secured together by bolts 11 and are spaced apart by sleeves 12 positioned about the bolts between the beams. Each of the carriages comprises a hollow body portion 15 receiving the boom *a* and carrying at each side rollers 16 which travel on the trackways formed by the horizontal webs of the boom. Attached to the bottom of each carriage is a plate 18 each end of which is provided with a hooked portion 19. Attached to each

of these plates 18 are one or more chains *c*, each chain having at its free end a hook which, as shown, is adapted to be hooked over the hooked ends 19. In the present instance, I have shown each carriage as being 60 provided with two chains so that two rolls of paper or the like may be transported at the same time, if desired.

Each of the carriages *b* is provided with an ear 20 movable in the space provided 65 between the two angle irons 10 of the boom and connected to these ears are racks 21 meshing with a pinion 22 fixed to a shaft 23 located centrally of the boom and carrying on its outer end the hand wheel *d*. It 70 will be seen that upon turning the hand wheel *d*, the carriages will simultaneously travel in opposite directions on the boom *a* and thus the distance between the carriages 75 may be quickly varied to accommodate different lengths of rolls or other articles to be transported. The racks 21 are maintained in meshing relation with the pinion 22 by rollers 24. The boom is reinforced by plates 25 through which the shaft 23 extends.

Connected to the boom *a* by means of the shaft 23 is a yoke *e* composed of a pair of side plates or arms 27 and a cross member 28 carrying an eye-bolt 29 which receives 85 a hook on the lower end of a chain of a derrick or the like. The shaft 23 passes through openings in the arms 27 and constitutes the sole connection between the boom and yoke so that when the crane is 90 lifted the friction between the yoke *e* and the shaft 23 is sufficiently great to prevent accidental rotation of the latter.

A roll of paper *y* may be connected to the chains *c* by bars *f* positioned in the 95 ends of the opening or core *x* of the roll. Heretofore, bars of this sort, owing to the weight of the paper rolls and the leverage exerted, frequently resulted in mutilation of the paper about the openings receiving the 100 bars or in breaking down the cores *x* where the paper is rolled on such cores. The bars of the present invention are constructed to obviate this difficulty. Each is provided with a relatively long spindle entering the 105 opening of the core of the roll of paper. The opposite ends of each spindle are similarly tapered in opposite directions as at 33, 34, so that relatively long substantially parallel bearing surfaces between the core 110

wall and the spindle are obtained thereby greatly reducing likelihood of cracking or breaking down the wall of the opening. On the protruding end of the bar is a grooved head 32 about which passes the chain c. The spindle portion is considerably longer than the protruding end of the bar so as to reduce leverage.

It is, of course, obvious that my invention is susceptible of various modifications and changes which are within the spirit of the invention without departing from the scope of the following claims, it being understood that the present disclosure of my invention is by way of illustration only and it is not to be taken as restrictive of my conception.

I claim as my invention:—

1. In an apparatus of the class described, 20 a boom provided with trackways, a pair of carriages supported directly on said trackways for adjustment and adapted to support an article therebetween, a manually rotatable shaft journaled centrally of said 25 boom, a pinion fixed on said shaft, and oppositely extending racks connected to said carriages and meshing with said pinion.
2. In an apparatus of the class described, 30 a boom comprising a pair of beams connected in spaced apart relation, a pair of carriages adjustable on said boom, and means located between said beams for moving said carriages in opposite directions on said boom.
3. In an apparatus of the class described, 35 a boom comprising a pair of channel irons connected together in spaced apart relation, a pair of carriages adjustable on the tracks formed by the horizontal webs of said boom, 40 a pinion located between said beams, oppositely extending racks connected to said carriages between said beams and meshing

with said pinion, and a hand wheel for rotating said pinion.

4. In an apparatus of the character described, 45 a boom, a pair of carriages adjustable thereon, means including a shaft journaled in said boom for moving said carriages longitudinally of said boom, and an attachment connected to said shaft for lifting said boom, said shaft being held against accidental rotation when the apparatus is lifted owing to the friction between the shaft and the bearings in which it is mounted.

5. In an apparatus of the class described, 50 a boom provided with trackways, a pair of carriages adjustably mounted thereon, a manually rotatable shaft journaled in bearings in said boom, a pinion thereon, oppositely extending racks connected to said carriages and meshing with said pinion, and a yoke straddling said boom and connected thereto by said shaft whereby rotation of the shaft is prevented when the 55 apparatus is lifted.

6. In an apparatus of the class described, 60 a boom, a pair of carriages thereon and each having a pair of hooked portions, a pair of chains connected to each carriage and each having a hook on its free end adapted to be hooked over the hooked portions of said carriages.

7. In an apparatus of the class described, 65 a boom, a pair of carriages thereon and each provided with a depending plate having hooked ends, a pair of chains connected to each plate and each chain having a hook on its free end adapted to be hooked over the hooked ends of said plates.

HOWARD PARKER.
